US00D733710S

(12) **United States Design Patent**
Huebner

(10) **Patent No.:** **US D733,710 S**
(45) **Date of Patent:** **** Jul. 7, 2015**

(54) **COORDINATE INPUT DEVICE**

(71) Applicant: **Wacom Co., Ltd.**, Kazo-shi, Saitama (JP)

(72) Inventor: **Volker Huebner**, Erkrath (DE)

(73) Assignee: **Wacom Co., Ltd.**, Kazo-shi (JP)

(**) Term: **14 Years**

(21) Appl. No.: **29/508,258**

(22) Filed: **Nov. 4, 2014**

Related U.S. Application Data

(63) Continuation of application No. 29/460,813, filed on Jul. 15, 2013, now Pat. No. Des. 719,161.

(30) **Foreign Application Priority Data**

Jan. 18, 2013 (JP) 2013-000804

(51) **LOC (10) Cl.** **14-02**

(52) **U.S. Cl.**

USPC **D14/390; D14/341**

(57) **CLAIM**

The ornamental design for a coordinate input device, as shown and described.

DESCRIPTION

FIG. 1 is a bottom front right perspective view of a coordinate input device according to my new design;
FIG. 2 is a front view of the coordinate input device of FIG. 1;
FIG. 3 is a rear view of the coordinate input device of FIG. 1;
FIG. 4 is a left side view of the coordinate input device of FIG. 1;
FIG. 5 is a right side view of the coordinate input device of FIG. 1;
FIG. 6 is a top plan view of the coordinate input device of FIG. 1; and,
FIG. 7 is a bottom plan view of the coordinate input device of FIG. 1.

The broken lines shown in the drawings represent portions of the coordinate input device that form no part of the claimed design.

1 Claim, 7 Drawing Sheets
